INVENTOR.

P. D. BURKE

BY *Milton B. Crandall,*

ATTORNEY

UNITED STATES PATENT OFFICE.

PETER D. BURKE, OF ROSWELL, SOUTH DAKOTA.

CLEVIS.

1,197,008.

Specification of Letters Patent.

Patented Sept. 5, 1916.

Application filed October 7, 1915. Serial No. 54,534.

To all whom it may concern:

Be it known that I, PETER D. BURKE, a citizen of the United States, and a resident of Roswell, in the county of Miner and State 5 of South Dakota, have invented certain new and useful Improvements in Clevises, of which the following is a specification.

The present invention relates to clevises and more particularly to clevises used on 10 whiffletrrees, plow-beams, drags, etc.

The invention has for its primary object the production of a clevis embodying certain novel features of construction whereby the clevis pin is removably, yet securely 15 locked in the clevis.

Another object of the invention is the production of an improved locking clevis inexpensive and simple in construction, and thoroughly dependable in operation.

With these and other objects in view, the invention consisting in the construction, combination and novel arrangement of parts, will be fully understood from the following description, reference being had to the accompanying drawings, which form a part 20 of this application and in which like characters of reference indicate corresponding parts throughout the several views, of which:—

Figure 1 is a side elevation of a clevis constructed in accordance with the invention; Fig. 2 is a plan of the same, the clevis-pin being omitted; Fig. 3 is a transverse section of the same, taken through the eyes 30 of the clevis; and Fig. 4 is a perspective view of the clevis pin.

Although I have illustrated and herein-after described the preferred embodiment of the invention, I would not be understood 40 as being limited to the specific structure chosen for the illustration, for various alterations in the details of construction and arrangement of parts, may be made without departing from the spirit and scope of the 45 invention as defined in the appended claims.

Referring, now, to the illustrations, 5, represents the bow of the clevis, which is of spring material and includes arms, 6 and 7, formed at their ends with eyes, 8 and 9, 50 respectively. The eyes are mutually alined

and encircle a clevis-pin 10, threaded into the eye, 9. The clevis-pin is formed with a square, or flat-sided head, 11, which may be formed integrally with a thumb-grip, 12, for conveniently manipulating the pin.

The outer face of the eye, 8, is provided with a square or flat-sided recess, 13, adapted to receive the correspondingly-shaped head of the clevis-pin.

To insert the clevis-pin, the arm, 6, of the 60 bow is first sprung inwardly, as indicated in dotted lines in Fig. 1, and the pin then threaded into the eye, 9. The pin is then turned to a position where the head thereof will be received by the recess, 13, when the 65 arm, 6, is permitted to assume its normal position, and thus prevent rotation of the pin.

It is apparent that prior to unscrewing the clevis-pin to remove it, the arm, 6, must 70 again be sprung inwardly as previously stated.

Having thus described my invention, what I claim as new and desire to secure by Letters Patent of the United States, is:—

1. An article of the class described comprising a clevis-bow having inwardly-yieldable arms each provided with an eye, and a pin removably inclosed by said eyes, said pin being threaded into the eye of one of 80 the arms and provided with a head, adapted to be normally engaged by the other arm to prevent rotation of the pin, and disengaged from the latter arm when either arm is sprung inwardly.

2. An article of the class described comprising a clevis-bow having inwardly-yieldable arms, each provided with an eye, and a pin removably inclosed by said eyes, said pin being threaded into the eye of one of the 90 arms and provided with a flat-sided part, the other of said arms having a part normally engaged with said flat-sided part to prevent rotation of the pin, and disengaged from said flat-sided part when either arm is 95 sprung inwardly.

In testimony whereof I have hereunto set my hand.

PETER D. BURKE.

Copies of this patent may be obtained for five cents each, by addressing the "Commissioner of Patents, Washington, D. C."
